UNITED STATES PATENT OFFICE.

HENRY TRENCHARD, JR., OF BROOKLYN, NEW YORK, ASSIGNOR TO TENSION ENVELOPE COMPANY, INC., OF BROOKLYN, NEW YORK, A CORPORATION OF NEW YORK.

FASTENER-AFFIXING MACHINE.

Original application filed December 31, 1917, Serial No. 209,729. Divided and this application filed March 1, 1919. Serial No. 280,183. Renewed February 9, 1923.

To all whom it may concern:

Be it known that I, HENRY TRENCHARD, Jr., a citizen of the United States of America, residing in the borough of Brooklyn, in the city of New York and State of New York, have invented an Improvement in Fastener-Affixing Machines, of which the following is a specification.

The present invention relates to paper working machinery and more particularly to a machine for applying fasteners to an envelope or other blank.

It is an object of the invention to provide improved fastener applying mechanism.

15 The present application is a division of an earlier application filed by me on December 31, 1917, Serial No. 209,729, which application was a continuation in part of a still earlier application filed by me December 20, 1915, Serial No. 69,392, now Patent No. 1,258,829 dated March 12, 1918.

The invention has been developed and for convenience will be described as embodied in a machine for applying so-called 25 "double button and string" fasteners to envelopes.

For convenience in the description of the particular embodiment of this invention, it may be noted that such envelopes are generally 30 provided with a comparatively stiff fastening washer upon the outside of the body of the envelope united thereto preferably by means of an eyelet which is upset to engage the washer and hold it securely in position in relation to the body of the envelope. A similar fastening washer is similarly affixed to the flap of the envelope and preferably a comparatively light reinforcing washer is used upon the inside of 40 the flap; the two being fastened by an eyelet passed through the washers and through the envelope flap. The string, which is used to effect the closure of the envelope, preferably has one end fastened under the eyelet which attaches the cooperating washer to the flap of the envelope.

A preferred embodiment of the invention has been herein selected for purposes of illustration and explanation and is shown 50 in the accompanying drawings, wherein—

Figure 1 is a front elevation of the machine;

Figure 2 is a side elevation viewed from the right of Figure 1;

Figure 3 is a top plan view of the machine with certain parts removed for clearness;

Figure 4 is a vertical section on the line 4—4 of Figure 3;

Figure 5 is a vertical section on the line 5—5 of Figure 3;

Figure 6 is an enlarged view of a portion of Figure 5;

Figures 7, 8 and 9 are detailed views of a preferred eyelet escapement mechanism;

Figures 10 and 11 are detail views of a preferred clutch mechanism;

Figure 12 is a view of a preferred eyelet feeding mechanism;

Figure 13 is a detail view of a preferred 70 tape feed actuating mechanism;

Figure 14 is a vertical cross-section on the line 14—14 of Figure 1;

Figure 15 is a similar section on the line 15—15 of Figure 1 looking in the opposite 75 direction from the preceding figure;

Figure 16 is an assembly view of a preferred string feeding and cutting mechanism;

Figures 17 and 18 are detail views of the 80 string cutting mechanism;

Figures 19, 20 and 21 are detail views of the string feeding mechanism; and

Figure 22 shows an envelope punched with a fastener such as may be attached by 85 the machine herein shown.

In the following description of the illustrative embodiment of the invention, the general structural features of the machine will first be described and then, in the sequence indicated, the illustrative mechanism for affixing the fastener and washer to the body of the envelope; the illustrative mechanism for forming and affixing the fastener and reinforcing washer to the flap of the envelope; and lastly the illustrative mechanism for feeding, fastening and cutting the string.

Referring to the drawings it will be seen that the greater part of the mechanism is 100 mounted upon a bed-plate or table 1 supported upon standards 2. A main shaft 3, journalled in suitable bearings upon the table 1, is provided with a balance wheel 4

and is adapted to be connected with a driving pulley 5 by a suitable clutch mechanism located at the right hand side of the machine. The driving wheel 5 carries a 5 jaw 6 and is, during the operation of the machine, rotated continuously from a suitable source of power.

The operation of the machine to affix the "double button and string fastener" is preferably accomplished in one revolution of the 10 main shaft 3 and the clutch mechanism is therefore designed to rotate the main shaft through one revolution and then automatically disengage. A clutch collar 7 is keyed 15 to the main shaft (see Figures 10 and 11) and is slidable thereon. This collar has jaws 8 to co-operate with jaws 6 on the hub of the driving pulley which rotates freely on the main shaft, and a spring pressed plunger 9 tends normally to force the jaws into 20 engagement. A flange 10 upon the collar 7 has a cam surface 11 and, as shown in Figure 11, this cam surface bears against a stud 12 which holds the collar 7 away from jaws 6. The stud 12 is held normally in the position 25 shown in Figures 2 and 10, by a spring 13 which is attached to the bed of the machine and to a lever 14 passing through the lower end of the stud. A treadle 15 is connected 30 by suitable links 16 and 17 with the lever 14 so that upon depression of the pedal and its immediate release, the collar 7 will be forced to the right in Figure 10 to engage jaws 6 and 8 and rotate the main shaft 3 35 through one revolution, the stud 12 co-operating with the cam 11 to withdraw the collar 7 toward the end of the single revolution.

As shown in Figure 3 a notched collar 18 40 is fast to the main shaft 3 and a spring pressed lever 19 engages the notch in the collar 18 to prevent the back lash of the main shaft.

Coming now to the mechanism for affixing the fastening washer to the body of the envelope and referring particularly to Figures 3 and 4, means are provided for feeding through a strip of tape, forming a washer from the tape, feeding an eyelet into 45 the proper position and actuating the washer forming mechanism to affix the washer to the body of the envelope. In Figure 3 it will be seen that shoe 20 projects from a stationary part of the machine and carries 50 an anvil 21. A light spring guard 22 is fastened to the outer end of the shoe and overlies the anvil 21. This spring serves to press the body of the envelope away from the anvil when the fastening eyelet has been upset 55 and contributes to the speed of operation of the machine by permitting a direct withdrawal of the envelope. The shoe, anvil and releasing spring are shown in section in Figure 4. A light spring 256 (see Fig. 3) 60 serves to press the envelope flap toward the

side of the shoe so that it may be quickly withdrawn from the machine at the completion of operation.

Slidably mounted in the machine, as shown in Figure 3, is a reciprocating plunger 23. Suitable means are provided for actuating this plunger from the main shaft, the same being herein shown as co-operating beveled gears 24 and 25; the latter being mounted upon a shaft 26 suitably journaled 70 in the frame, and carrying at its end opposite the gear 25, a crank arm 27 to which a connecting rod 28 is attached. The connecting rod 28 is attached at its other end to a cross bar 29 which is fastened to the plunger 23 by means of a block 30 and collars 31. Through this connection the plunger 23 will be moved forward and back upon a single revolution of the main shaft. Referring to Figure 4 a second plunger 32 is 75 mounted below the plunger 23 and carries at its end a punch 33. Suitable means are provided to actuate the plunger 32 simultaneously with the plunger 23, a block 34 connecting the two at their outer ends. The plunger 23 carries a hollow punch 35 with a sliding pin 36 pressed forward by a spring 37 which is mounted within the punch 35. A die plate 38 is rigidly attached to the machine and is provided with a hole 39 to co-operate with the punch 35 and a hole 40 to co-operate with the punch 33. A vertical channel 41 is formed by a guard plate 42 interposed between the die plate and the punches. Through this channel is drawn a strip of tape 43 from a supply roll 44, shown in Figures 1 and 2 as mounted upon a spindle 45 projecting from one of the standards of the machine.

Suitable means are provided to draw the 105 tape step by step through the channel 41, the increments of movement corresponding to the distance between the axes of the punches 33 and 35 for a purpose which will hereafter appear. Tape feeding means are 110 herein shown as a pair of co-operating feed rolls 46 and 47, shown diagrammatically in Figure 4, and also in Figures 2 and 3. Suitable means are provided to actuate the feed rolls, the same being herein shown as a cam 115 operated ratchet and pawl mechanism. The upper feed roll is mounted upon a shaft 48 suitably journaled in bearings which permit it to be pressed toward the co-operating feed roll 47 by set screws 49. This shaft 120 also carries another feed roll which will be later referred to. A ratchet 50 (see Figure 13) is fast to the shaft 48 and a spring pressed pawl 51 is carried upon a pivoted arm 52 which is actuated through a link 53 by an arm 54 upon a vertically slidable standard 55 suitably journaled in the bed-plate of the machine and held in lowered position by a spring 56. The arm 54 carries a roller 57 which rides upon a cam 58 fast to 125 130

the main shaft 3. The cam is so placed upon the shaft that the feed rollers will be actuated to move the tape forward when the punches are free therefrom.

5 Suitable means are provided for feeding an eyelet so that it may be picked up by the pin 36, Figure 4, in the plunger 35 and carried forward, passed through a hole in the washer and thereafter upset against the anvil 21 to fasten the washer to the envelope body. Such means are herein shown as follows: Referring to Figure 1 a suitable eyelet selector box 60 is mounted upon a shaft 61 journaled in suitable bearings above the machine. The eyelet box, shown in more detail in Figure 12, may be of any suitable construction adapted to deliver eyelets to a channeled gutter leading to the eyelet upsetting mechanism. The box is rotated from the main shaft through belts 62 and 63 running over pulleys 64, 65, 66 and 67.

10 The eyelet box delivers eyelets to the gutter 70 and the eyelets will slide down the gutter until they reach an escapement mechanism, shown in Figures 7, 8 and 9. This escapement mechanism is adapted to release the eyelets one at time and permit the released eyelet to fall to the bottom of the gutter where it is in position for engagement by the upsetting mechanism. Referring particularly to Figures 7, 8 and 9 it will be seen that the escapement mechanism comprises a reciprocatory member 71 having two knife edges 72 and 73 staggered in 15 relation to the gutter. As shown in Figure 7 the eyelets are intended to pile up and be caught upon the upper knife edge 72. Upon a reciprocation of the member 71 to the right, the knife edge 72 will release an eyelet from the column of eyelets and permit it to drop, against the knife edge 73. Upon the reverse reciprocation to the left, knife edge will pass between the eyelet resting upon 73 and the one above it while 73 20 will pass out of the way and permit the lowest eyelet to drop.

25 The escapement slide 71 is actuated by the ball crank lever 74 having connection through a link 75 with an arm 76 carried by the feed roll actuating arm 54. Thus when the feed roll is actuated to move the strip forward, the eyelet escapement mechanism will be actuated to drop a single eyelet down the chute.

30 The lower end of the gutter is formed in a pair of doors or gates, one of these gates 77 being shown in Figure 4 as pivoted at 78 and held in normally closed position by a spring surrounding pivot. The eyelet sliding down the gutter from the escapement mechanism is stopped and held in alignment with the pin 36.

35 The operation of the mechanism just described in applying the fastening washer to the body of the envelope will be briefly de-

scribed before the description of the remaining parts of the machine is taken up.

The tape 43 being in position, each reciprocation of the punch 33 will form a small hole therein. Assuming that this hole 40 has been made and the tape moved forward one step so that the small hole in the tape is aligned with the center of the punch 35, the operation of this portion of the mechanism will be as follows: An envelope having 45 been inserted over the shoe 20, the treadle may be depressed to release the clutch and cause the rotation of the main shaft. This moved the punches 35 and 33 forward and the first result to be noted is that the pin 36 50 will pass through the eyelet which is in position at the bottom of the gutter. Then the forward end of the punch 35 will open the gates 77 and the pin will pass through the small hole in the tape 43 until the end of the 55 pin contacts with the envelope body and presses against the anvil 21. The plunger 35 will move forward until it contacts with the tape 43 and forces it against the aperture in the die plate 38 whereupon a portion of the 60 tape will be punched out to form a washer, supported by the pin 36, which as the punch proceeds is being pressed back against the spring 37. The washer thus formed is carried forward by the punch and pin and positioned against the envelope body. Finally the eyelet will be forced through the hole in the washer and through the material of the envelope and upset against the anvil 21. At 65 the same time another small hole has been 100 formed in the tape 43 by the punch 33. The eyelet having been upset the punches will be retracted and as soon as they have cleared the die plate 38 the cam 58 may actuate the feed mechanism to move the tape forward 105 one step. As soon as the gates 77 have closed behind the punch 35, the eyelet escapement mechanism may be actuated to drop another eyelet into position; thus completing a 110 single cycle of operation of this part of the apparatus.

Proceeding with the description of the mechanism, the means for forming and affixing a reinforcing washer to the flap of the envelope is best shown in Figure 5 and its 115 relative location to the mechanism just described is best shown in Figure 3. Referring to Figure 5, a reciprocating plunger 80 is suitably mounted in the bed of the machine and is adapted to be actuated in unison with the plunger 23. It is connected to the cross bar 29 by a block 81 as shown in Figure 3. Just below the plunger 80 is a plunger 82 also fastened in the block 81. The end of the plunger 80 forms a punch which 120 operates with a hole 83 in a die plate 84 and the plunger carries an upsetting anvil 85. The plunger 82 carries a punch 86 to operate with a hole 87 in the die plate 84. A channel 88, Figure 5, is formed between the 130

die plate 84 and the two punches and through this channel is passed a strip of reinforcing washer material 89. This strip is drawn from a supply roll 89', Figure 1, 5 mounted upon a spindle 89" projecting from one of the standards 2 and is led up over a guide roll 90 and between feed rolls 91 and 92; the feed roll 91 being mounted upon the same shaft 48 which carries the feed roll 46 10 and the feed roll 92 being mounted upon a shaft 93 upon which the feed roll 47 is also mounted. The feed roll 91 is rotated with feed roll 46 and the tape 89 is moved forward step by step as is the tape 43. Thus at 15 each reciprocation of the block 81 the punch 86 will form a small hole in the tape and the punch 85 will cut out a portion of the tape to form a washer and carry it forward for a purpose which will appear later. 20 Aligned with the plunger 80 is a cooperating reciprocating plunger 100 slidably mounted in the frame of the machine. Just beneath the plunger 100 is a smaller plunger 101 corresponding to the plunger 82. These 25 two plungers are actuated from the main shaft 3 through beveled gears 102 and 103 best shown in Figure 3. The bevel 103 is mounted upon a shaft 104 suitably journaled in the frame of the machine and this 30 shaft carries a crank arm 105 which is connected by a connecting rod 106 with a block 107 secured to the plunger 100. The plunger 101 is suitably connected with the plunger 100. At each revolution of the main shaft 3 35 the plungers 100 and 101 are moved forward and back as in the case of the other plungers.

The end of the plunger 100 forms a punch 109 while the end of the plunger 101 carries 40 a punch 110. A die plate 111 is rigidly mounted upon the machine and is provided with a hole 112 to cooperate with the punch 109. It is also provided with a smaller hole 113 to cooperate with the punch 110. 45 Between the die plate 111 and the ends of the plungers is a guide plate 114 which forms a channel 115 through which a strip of tape 116 is drawn by suitable feed rolls.

Within the punch 109 is a pin or rod 117 50 which is free to slide therein and is pressed normally outward by a spring 118. This spring is best shown in Figure 6 which is a horizontal section through the center line of the plunger 100. It is desired to have the pin 117 projected from the punch 109 at the beginning of the cycle of operation of the machine for purposes which will herein-after appear. Suitable means are therefore 55 provided to release the pin upon the start of operation; the same being herein shown as a trigger mechanism best illustrated in Figure 6. Attached to a fixed abutment is an arm 119 pivoted at 120 and free to rotate only in a clockwise direction on the pivot 60 from the position shown. Pivoted at 121 within the plunger is a trigger 122 which has an outwardly projecting arm 123 carrying an upstanding pin 124. The plunger 100 is shown in its completely retracted position in Figure 6. Upon forward movement of the plunger the pin 124 will contact with a cam surface 125 of a cam plate 126 fastened to the underside of the arm 119. The arm being restrained from movement toward the punch, the trigger will be drawn away from the enlarged end of the pin 117 and the pin will be released and shot forward by the spring 118. As the plunger moves forward the pin 124 will move along the cam plate 126 until the arm 123 contacts with a spring 127 which tends to hold the arm 119 in the position shown. At this time the end of the pin 117 will have come in contact with the advancing anvil 85 on the plunger 80 and be held from further forward movement so that the relative movement of the pin 117 with respect to the plunger 100 will be toward the right to compress the spring 118. Therefore as the plunger progresses further toward the left, the trigger 122 will bear 85 against the enlarged end of the pin 117 and finally snap behind the enlarged end so that the relative position of the plunger, pin and trigger will be the same as that shown in Figure 6. At about this time the plunger will be retracted from its advanced position and the pin 124 on the trigger arm will pass under the arm 119 and contact with the cam surface 128 on the cam plate 126. The arm 119 will be rotated slightly in a clockwise direction during the retractile movement of the punch until the parts come substantially into the position shown in Figure 6 when the arm 119, urged by the spring 127 will snap back into the position 90 shown.

Means are provided for drawing the tape 116 through the channel 115 and are substantially similar to corresponding means acting upon the other tapes. The tape roll 130, Figure 1, is supported upon a spindle 131 attached to one of the standards of the machine and the tape is drawn from this roll through the channel, over a guide roll 132 and between feeding rolls 133 and 134. The feed roll 133 is mounted upon a shaft 135 which is journaled in sliding bearings so that the feed rolls may be brought together by set screws 136. 100

As in the case of feed rolls 91 and 46, suitable means are provided for intermittently rotating the feed roll 133 to feed the tape step by step. A ratchet 137 is fast to the shaft 135 and a spring pressed pawl 138 mounted upon an arm 139 is actuated through a suitable link connection 140 from an arm 141 carried by a standard 142. The arm 141 has a roller 143 contacting with a cam 144 upon the main shaft 3 and the roller 105 is maintained in contact with the cam by a 110

115

120

125

130

spring 145. Eyelet feeding means substantially like that described in connection with the punch 35 are utilized to position an eyelet in front of the punch 109. The eyelet feed box 150 is driven through belts 151 and 62 the former running over pulleys 152 and 153. A gutter 154 leads from the eyelet box to the hinged gates 155 which position the eyelet at the axis of the pin 117.

10 An escapement mechanism similar to that operating upon the eyelets in the gutter 70 is provided to operate upon eyelets in the gutter 154. An escapement bar 156 is shown in Figure 15 and the link connections 157 to an arm 158 upon the arm 141.

15 The operation of the parts just described may be understood from Figure 5. First with respect to the anvil carrying plunger 80. It will be observed that upon reciprocation this plunger will move toward the tape 89; the anvil pin passing through a hole in the tape which has been punched at the previous operation by the punch 86. The end of the plunger 80 coming into contact with the tape will punch out a portion 20 of the tape to form a washer and carry it forward.

25 Upon the other side, the initial movement of the plunger 100 will operate to release the pin 117 which will be moved forward, passed through an eyelet, which is positioned in front of it, through a hole in the tape 116 which has been punched in the previous operation by the punch 110 and will 30 come in contact with the anvil pin 85 before the plunger 110 has travelled very far. During further forward movement of the plunger 100 the string feeding means, which are about to be described, may operate. 35 Upon further movement the punch 109 will open the gates 155, pass the guide 114 and contact with the tape 116, cutting out a portion to form a washer and carrying the eyelet and washer forward to the central position. The plungers 80 and 100 thus form 40 the washers or buttons and position them against opposite sides of the flap or blank, and the actuation of the plungers not only forms the washers and positions them 45 against the envelope, but also sets the eyelet which serves as a fastener by which the washers are affixed to the envelope flap. The description of the completion of the 50 operation will be reserved until the string feeding means has been described.

55 The attachment of the string to the flap of the envelope is preferably effected by looping the string around the pin 117 before the dies have been brought together to upset the eyelet. Thus the string is looped in 60 position to be fastened between the upset flanges of the eyelet. It will readily be observed how this is effected while the reinforcing washer is being formed by the 65 punch 85, and the fastening washer is being

formed by the punch 109. After the envelope flap has been placed alongside the die plate 84 and the treadle 15 depressed, the initial movement of the plunger 100 will release the pin 117 and permit it to shoot forward into contact with the envelope flap. Then, while the punches are coming together the string may be wound upon the pin and thereafter caught between the envelope flap and the reinforcing washer and firmly held 70 there by the flanges of the eyelet.

75 Means for accomplishing this result are herein shown as a hollow gear 200 mounted within a suitable housing and rotating concentrically about the pin 117 and of sufficient size to permit the punch 109 to pass therethrough. This gear is rotated from the main shaft 3 by a suitable train of gearing comprising the gears 201, 202 and 203 and is preferably rotated at a greater speed 80 than the main shaft. In this instance the gear 200 which, with its associated parts, will hereinafter be termed the "looper" 85 makes four revolutions to one revolution of the main shaft. Means are provided on the gear to grasp the end of a string which is presented to the looper by means hereinafter described, the string grasping means being herein shown as a substantially U-shaped member 204, Figure 20, normally spring 90 pressed against the face of the gear but adapted to be extended from the face of the gear at the proper moment in the operation of the machine when it is desired to grasp a piece of string presented thereto. This U-shaped member 204 extends through the gear and is fixed to a ring 205 having a cam surface 206. The construction of this looper will be more readily seen from Figures 19, 20 and 21 which are respectively an 95 end view, front view and cross-section of the looper. The ring 205 is normally held away from the gear by springs 207 and its movement is limited by the string engaging member 204. Thus, it will be seen that 100 when an end of a string is placed under the member 204, it will be firmly grasped between this member 204 and the face of the gear in the absence of any control thereof by the ring 205 with its cam surface 206.

105 Means may be provided to control the opening and closing of the member 204 for the purpose of threading the string thereunder, the said means being herein shown as a cam 208 mounted upon a lever 209 and controlled by a cam 210 upon the main shaft (see Figure 15). As this particular mechanism is designed to operate, it is desirable to have the looper opened for grasping the string once in its four revolutions, that is, 110 at a time when the pin 117 is extended. It will therefore be seen that when the cam 208 is brought to the position shown in Figure 15, the looper, rotating in a counter-clockwise direction will be opened by the 115 120 125 130

cam 208 for threading the string. As the looper continues to rotate the high point of the cam surface 206 is rotated past the cam 208 and the string engaging member 204 will grasp the string end which has been presented to it and will wind the string about the pin 117 until the string is released or withdrawn from the looper.

- Means may be provided to present the end 10 of a string to the looper mechanism so that it may be engaged by the member 204 and the rim of the gear 200, the same being herein shown as a reciprocating string carrying member 215 and its associated parts. 15 This string carrying member is provided with a finger 216 having a resilient side plate 217 to engage the string when it is threaded therethrough and to tension the string during the succeeding operations. 20 The string carrying member 215 is mounted in a guideway 218 and is reciprocated by a crank arm 219 and link 220, the crank arm being mounted upon a shaft 221 which in this particular instance, is driven in synchronism with the main shaft 3 through a 25 train of gears 222, 223, 224, 225, 226 and 227.

Means may be provided to sever the string, the same being herein shown as shears 230 having a fixed blade 231 and movable blade 232 and mounted upon an oscillating member 233 pivoted at 234 upon the guideway. The two blades of the shears are pivoted at 235 and are held in operative relation by any suitable means herein shown 35 as a stud and spring 236. Suitable means may be provided to bring the shears into position for cutting the string, the same being herein shown as a cam 237 upon the oscillating shears mounting 233 adapted to 40 be engaged by an anti-friction roller 238 upon the string carrying member 215 to oscillate the shears and bring them into operative position for cutting the string. The shears mounting is shown in its normal 45 position in Figures 15 and 17 and is yieldingly held in this position by a spring 239 attached to the shears mounting and to an arm 240 which in turn is rigidly attached to the guideway 218.

50 Means may be provided to operate the shears to cause them to cut the string upon their being brought forward through the aperture 241 in the guideway, such means being herein shown as an anti-friction roller 55 242 upon the rearwardly extending movable blade 232 of the shears. (See Figures 17 and 18). This roller 242 is adapted to be engaged by a pair of cams 243 and 244 which cause the shears to close and open 60 respectively. It will be observed that when the shears mounting is oscillated upon the pivot 234 the shears will be swung forward until the anti-friction roller 242 contacts with the cam 243. Upon further forward 65 movement of the shears the cam 243 will

operate to bring the cutting edges of the shears together and thereupon the machine being so organized as to bring the string between these cutting edges, the string will be severed just above the threader. As the 70 string carrying member is moved upward by the crank and link connection with the shaft 221 the roller 238 upon the string carrying member will be released from engagement with the cam 237 upon the shears 75 mounting and allow the same to resume its normal position under the action of the spring 239. The rearward movement of the shears will bring the shears operating roller 242 in contact with the cam 244 which will 80 cause the shears to be opened in readiness for the next forward movement preceding the cutting of the next length of string.

To assist in properly locating the envelope 85 an adjustable table 250, as shown best in Figures 1 and 2, is positioned in front of the machine and supported in a bracket 251. This table may be raised or lowered by means of a screw 252 which can be rotated by a handle 253. The screw is 90 threaded in a bracket 254. The table may be adjusted to a proper horizontal plane by another screw 255 shown in Figure 2.

The operation of the machine as a whole 95 may be summarized as follows: Starting with the several parts of the apparatus in the positions shown in Figures 1, 2, 4 and 5, and referring particularly to those figures, an envelope to which the string closure is to be affixed may be inserted in the machine by extending the flap into the space between the die plate 84 and the looper 200; the shoe 20 being inserted in the envelope so that the body of the envelope comes between the shoe 20 and the die plate 80. The table 100 250 will of course be previously adjusted to position the envelope properly. The envelope being in place the treadle 15 may be depressed to release the clutch mechanism and start the rotation of the main shaft 3. 105 The several plungers will start their forward movement at a relative speed depending upon the distance which they have to travel. The initial movement of the plunger 100 will release the pin 117 and shoot it 110 forward into contact with the envelope flap. The initial rotation of the string looper will cause it to grasp the string and wind the string about the pin while the several plungers are coming forward. When the main 115 shaft has made substantially one quarter revolution the several punches will have reached their respective tapes and cut out washers therefrom. In the case of the plunger 100 the punch will carry forward an 120 eyelet and washer upon the pin 117, while the plunger 80 cuts out and carries forward a reinforcing washer on the anvil pin 85, and the punch 35 cuts out and carries forward a washer and eyelet upon the pin 36. When 125 130

- the main shaft has completed about the first half of its revolution, the punch 35 will have a washer and eyelet in contact with the body of the envelope, the anvil 85 will hold the 5 reinforcing washer in contact with the inside of the flap of the envelope and the punch 109 will hold a fastening washer and eyelet in contact with the outside of the flap of the envelope, while the string will be wound 10 upon the pin 117 and when the eyelet on the pin has advanced far enough the string will ride up upon the shank of the eyelet. During this time the string carrier 215 will have descended in its guideway until the roller 238 is nearly in contact with the cam 235 of the shears mechanism. At the completion 15 of the first half revolution the punch 35 will force the eyelet carried by it through the paper of the body of the envelope and upset it 20 against the anvil thus securing the fastening washer to the body of the envelope, while the cooperating plungers 80 and 100 will force an eyelet through the fastening and reinforcing washers and the flap of the envelope and upset it to secure the washers and 25 string firmly thereto. At substantially this time the shears will be moved forward to cut the string at the proper point.
- During the second half revolution of the 30 main shaft the several plungers will be retracted to their starting positions, the tapes advanced one step and an eyelet dropped to the bottom of each gutter, and the string carrier will have returned to the position of 35 Figure 5 to place an end of the string where it can be grasped by the looper. This completes a single cycle of operation and places the machine in position for its next operation.
- It will be understood that it is not indispensable that the several parts of the machine be used in combination as their separate advantages may accrue from their independent use in any suitable machine, and 40 it is to be understood that the invention may be variously modified and embodied within the scope of the subjoined claims.
- I claim as my invention,
1. In a machine of the character described, the combination of a unitary washer forming and eyelet setting member, means to feed washer material thereto, means to feed an eyelet to said member, and means to actuate said member to form a washer and fasten 45 the same to a sheet of material by an eyelet.
  2. In a machine of the character described, the combination of a washer forming punch having an axially mounted eyelet carrying member, means to position an eyelet upon said eyelet carrying member, means to feed washer material past said punch, an upsetting anvil, and means to actuate the punch to form a washer and to affix the same to a sheet of material by upsetting the eyelet.
  3. In a machine of the character described, the combination of fastener setting mechanism, means for drawing a tape of washer material past the setting mechanism, means combined with the setting mechanism and coaxial therewith for cutting out a portion of said tape to form a washer, and means for actuating the setting mechanism to secure said washer to a sheet of material by a fastener.
  4. In a machine of the character described, the combination of coaxial washer forming and fastener setting mechanism, a tape supply of washer material located at one side thereof, tape feed rolls located upon the opposite side thereof, and means for actuating said feed rolls to draw the tape past the washer forming and fastener setting mechanism.
  5. In a machine for affixing a washer to a sheet of material the combination of means for feeding a strip of washer material by successive steps, combined eyelet setting and washer forming mechanism for forming a washer from the washer material at each step, and means to actuate a part of said last named mechanism from a washer forming position to an eyelet setting position.
  6. In a machine of the class described, an eyelet upsetting and washer cutting plunger, an eyelet positioning plunger, and means for actuating said plungers.
  7. In a machine of the class described, an eyelet upsetting and washer cutting plunger, an eyelet positioning plunger, and means for simultaneously reciprocating said plungers.
  8. In a machine of the class described, an eyelet upsetting and washer cutting plunger, an eyelet positioning plunger mounted within said cutting plunger and normally protruding from the end thereof, means for simultaneously moving said plungers, and means for arresting the forward movement of said positioning plunger without arresting the movement of said cutting plunger.
  9. In a machine of the class described, an eyelet upsetting and washer cutting plunger, an eyelet positioning plunger mounted within said cutting plunger for movement independent thereof and normally protruding from the end thereof, means for simultaneously moving said plungers, and a spring interposed between the inner end of said positioning plunger and the inner wall of said cutting plunger.
  10. In a machine of the class described, an eyelet positioning device, a washer material feed device, a pair of plungers, one mounted within the other for movement relative to each other, means for moving one of said plungers in one direction, means for retaining the other of said plungers under tension against movement in that direction, and means controlled by said first plunger upon

- reaching a predetermined point in its travel for releasing said retaining means of said second plunger.
11. In a machine of the class described, an eyelet positioning device, a washer material feed device, a pair of plungers, one mounted within the other for movement relative to each other, means for moving one of said plungers in one direction, means for retaining the other of said plungers under tension against movement in that direction, means controlled by said first plunger upon reaching a predetermined point in its travel for releasing said retaining means of said second plunger, and means for moving both of said plungers in unison in the opposite direction.
12. In a machine of the class described, a pair of plungers, means for locking said plungers for movement in unison in one direction, means for locking one of said plungers against movement in the opposite direction, and means for releasing said locking means when the other plunger has traveled a predetermined distance.
13. In a machine of the character described, an eyelet plunger and a cutting plunger, a common source of power for actuating said plungers, means for actuating said cutting plunger in one direction, spring means between said cutting and eyelet plungers for projecting the eyelet plunger relative to the cutting plunger, means for locking said eyelet plunger against forward movement so that the spring means between said plungers will be tensioned by forward movement of the cutting plunger, and means for releasing said locking means when said cutting plunger has traveled a predetermined distance.
14. In a machine of the class described, an eyelet plunger and cutting plunger, a common source of power for actuating said plungers, means for actuating said cutting plunger in one direction, spring means between said cutting and eyelet plungers for actuating the eyelet plunger in one direction, means for locking said eyelet plunger against movement under the action of the spring means so that the spring means between the plungers will be tensioned by the movement of the cutting plunger, means for releasing said locking means when said cutting plunger has travelled a predetermined distance, and means for locking said plungers together for movement in unison in the opposite direction.
15. In a machine of the class described, the combination with a main shaft, and an envelope positioning mechanism, of a washer feeding device for feeding washer material to said envelope, an eyelet feeding device for feeding eyelets to said envelope, a cutting and upsetting device for cutting a washer from said material and upsetting said eyelet, and means for actuating all of said devices from said shaft.
16. In a machine of the character described, in combination, opposed punches provided with eyelet setting means thereon, die plates disposed in front of said punches, means to feed washer material between the punches and die plates, and means for causing a relative movement between said punches and die plates to form washers and to affix said washers to an interposed blank by an eyelet.
17. In a machine of the character described, in combination, means for forming a washer, said means including a member for positioning the washer against one side of a blank, means for inserting a fastener from the opposite side through the blank and washer, the washer positioning member and the fastener inserting means being operable to affix the fastener, and means to actuate the washer positioning member and fastener inserting means to affix the washer by the fastener.
18. In combination, a unitary washer forming, washer positioning and fastener carrying member, an oppositely acting unitary washer forming, washer positioning and fastener setting member, and means to actuate said members relatively to form and position washers and to affix the same to an interposed blank by the fastener.
19. In a machine of the character described, in combination, means for forming and positioning a washer against one side of a blank comprising a die and a punch operating therethrough, means for inserting an eyelet from the opposite side through the said washer and blank, and means for actuating the aforesaid means to affix the washer to the blank by means of the eyelet.
20. In a machine of the character described, in combination, means for forming and positioning a washer against one side of a blank comprising a die and a punch operating therethrough, means cooperating with the punch for inserting an eyelet first through the washer and then through the blank, and means cooperating with said punch for setting the eyelet.
21. In a machine of the character described, in combination, a reciprocable washer forming punch carrying an eyelet set, an opposed washer forming punch carrying a cooperative eyelet set, means to position an eyelet to be carried forward by one of said opposed punches, and means to actuate the opposed punches to affix the washers to opposite sides of an interposed blank by upsetting the eyelet.
22. In a machine of the character described, in combination, a washer forming punch having an axially mounted longitudinally movable eyelet carrying member,

- an oppositely acting washer forming eyelet setting punch, and means to actuate said punches to form washers and to affix the same to an interposed blank by said eyelet.
23. In a machine of the character described, fastener setting mechanism for securing a fastener to a blank, means for forming a washer in fastener receiving position on each side of said blank, and means for actuating the fastener setting and washer forming means to secure the washers to the blank by the fastener.
24. In a machine of the character described, in combination, fastener setting mechanism for applying a fastener to a blank, means for forming a washer in fastener receiving position on each side of said blank, means for feeding a fastener to the fastener setting mechanism, and means for actuating the fastener setting mechanism to secure the washers to the blank by the fastener.
25. In a machine of the character described, in combination, fastener setting mechanism for securing a fastener to a blank, means for forming two separate reinforcing washers in fastener receiving position, means for feeding washer material to said forming means, and means for actuating the fastener setting and washer forming means to secure the washers to the blank by the fastener.
26. In a machine of the character described, in combination, a reciprocatory anvil, a reciprocatory set, means for forming a washer in the path of the set, means for forming a washer in the path of the anvil, and means for actuating the anvil and set to secure the washers to a blank by a fastener.
27. In a machine of the character described, in combination, opposed punches provided with eyelet setting means thereon, means to feed strips of washer material past said punches, die plates disposed in the paths of said punches, and means to actuate said punches toward each other through washer forming stations to an eyelet setting station.
28. In a machine of the character described, in combination, eyelet setting mechanism and washer forming mechanism comprising a punch and eyelet set having a diameter corresponding to the outside diameter of the washer and a second punch for punching a central hole in the washer, said punches being adapted to operate simultaneously upon a strip of washer material fed past the punches by successive steps.
29. In a machine of the character described, in combination, means for guiding a blank, means for feeding a strip of material to one side of said blank and means for puncturing said strip at predetermined intervals as the same is fed through said ma-
- chine, means for severing a punctured portion of said strip from the remainder thereof in eyelet receiving position, means for inserting an eyelet first through the punctured portion of said severed strip and then through a portion of the blank, and means for upsetting the said eyelet to clamp said portion of the strip and said blank together.
30. In a machine of the character described, in combination, punches for cutting out washers, means for feeding strips of washer material to said punches, means to actuate said punches to cut out perforated washers, and means cooperating with said punches and coaxial therewith to affix said washers to a blank by a fastener.
31. In combination, a unitary washer forming and fastener carrying member, an oppositely acting unitary washer forming and fastener setting member, and means to actuate said members relatively to form washers and to affix the same to an interposed blank by the fastener.
32. In a machine of the character described, the combination of fastener setting mechanism, means for forming a washer in fastener receiving position on one side of a piece of material, means for forming a washer in fastener receiving position on the other side of the piece of material, and means for actuating the fastener setting and washer forming means to secure the washers to an envelope by a fastener.
33. In a machine of the character described, the combination of a reciprocatory anvil, a reciprocatory set, means for feeding a fastener into the path of the set, means for forming a washer in the path of the set, means for forming a washer in the path of the anvil, and means for actuating the anvil and set to secure the washers to an envelope by a fastener.
34. In a machine of the class described, a fastener carrying plunger and a cutting plunger, a common source of power for actuating said plungers, means for actuating said cutting plunger in one direction, spring means between said cutting and fastener carrying plungers, means for locking said fastener carrying plunger against movement under action of said spring means so that the spring means will be tensioned by movement of the cutting plunger, and means for releasing said locking means when said cutting plunger has traveled a predetermined distance.
35. In a machine of the class described, a washer cutting plunger, a fastener carrying plunger concentric therewith, means for feeding a fastener to the fastener carrying plunger, and means for actuating the washer cutting plunger to cut a washer and for then actuating the fastener carrying plunger substantially as and for the purpose set forth.

36. In a machine of the character described, in combination, an anvil, a reciprocatory set, means for guiding a blank therebetween, means for forming a washer between the anvil and blank guiding means, means for forming a washer between the blank guiding means and the set and in line

with said set, and means for providing relative movement between the anvil and set to affix the washers to the blank by a fastener. ¹⁰

In testimony whereof, I have signed my name to this specification this 28th day of February, 1919.

HENRY TRENCHARD, JR.
